UNITED STATES PATENT OFFICE

1,989,658

DOOR

Edward Harrison McCloud, Columbus, Ohio, assignor to The Kinnear Mfg. Company, Columbus, Ohio, a corporation of Ohio

Original application April 28, 1932, Serial No. 607,976. Divided and this application February 7, 1933, Serial No. 655,630

5 Claims. (Cl. 20—20)

This invention relates to improvements in sectional doors of the overhead type, and has for its object to provide, in connection with such doors, means for ingress and egress in the form of a small 5 pass door or wicket door. This pass door or wicket door is so constructed, in connection with the sections of the overhead door, that it will not interfere with the operation of the sectional door and may be used for the passage of individuals 10 while the overhead door is in closed position.

It is particularly the object of this invention to provide a pass door, in connection with an overhead sectional door that is easily operated and will securely close the passageway therein and 15 prevent the leaking of water and air through the doorway, and to provide in connection with the sectional door, braces adjacent the pass or wicket door to prevent any unnecessary swinging movement of the door due to weakness caused by the 20 insertion of the wicket or pass door.

These and other advantages will appear from the following description taken in connection with the drawings.

This application is a division of my application 25 Ser. No. 607,976, filed April 28, 1932.

Referring to the drawings:

Figure 1 is an outside view of a sectional door of the overhead type, with a pass door inserted therein.

30 Figure 2 is an outside view of a part of a sectional door with the pass door connected therewith.

Figure 3 is an enlarged view of that part of the 35 sectional door immediately surrounding the pass door, with the pass door in closed position.

Figure 4 is a section on the line 4—4 of Figure 3.

Figure 5 is a section on the line 5—5 of Figure 2.

Figure 6 is a section on the line 6—6 of Figure 2.

40 Figure 7 is a section on the line 7—7 of Figure 2.

Figure 8 is a section on the line 8—8 of Figure 3.

Figure 9 is an enlarged view showing one of the 45 hinges connecting the pass door to one of the overhead door sections and the braces used in connection with the overhead door sections.

Figure 10 is a section on the line 10—10 of Figure 9.

Figure 11 is a section on the line 11—11 of Figure 9.

50 In Figure 1 there is shown a sectional door of the overhead type. In this figure the door is shown as composed of five sections, indicated by the numerals 1, 2, 3, 4 and 5, beginning from the upper section and ending with the lower section.

55 This figure shows the outside of the door.

These sections are hinged to one another by means of hinges 6. Certain of the sections have extending longitudinally thereof, across from one side to the other, a metallic stiffener 7 used to prevent the buckling or swinging of the door between the sides. Each section except the top section has on its top edge a notch 8 adapted to receive a correspondingly shaped tongue 9 on the lower edge of an adjacent section. These tongues and notches tend to prevent the passage of water from without, through the door, into the garage or building to which the door is applied. This notch and tongue structure also tends to prevent the passage of air through the crack between the door sections.

5 These sections are hinged to one another by means of hinges 6. Certain of the sections have extending longitudinally thereof, across from one side to the other, a metallic stiffener 7 used to prevent the buckling or swinging of the door between the sides. Each section except the top section has on its top edge a notch 8 adapted to receive a correspondingly shaped tongue 9 on the lower edge of an adjacent section. These tongues and notches tend to prevent the passage of water from without, through the door, into the garage or building to which the door is applied. This notch and tongue structure also tends to prevent the passage of air through the crack between the door sections.

10 In the door as a whole there is provided an opening 10, which extends across the section 4 and section 3, with the exception of the top rail 11, and across section 5, with the exception of the bottom rail 12. These rails are retained 15 in sections 3 and 5, to give greater strength and rigidity to the parts of the section door immediately around the pass door.

15 In the door as a whole there is provided an opening 10, which extends across the section 4 and section 3, with the exception of the top rail 11, and across section 5, with the exception of the bottom rail 12. These rails are retained 20 in sections 3 and 5, to give greater strength and rigidity to the parts of the section door immediately around the pass door.

This pass door has three sections, an upper section 13, an intermediate section 13a and a 25 lower section 13b. These sections are united to one another by means of hinges 14, as shown in Figure 3. The pass door is attached to one side of the opening therefor and to the door sections by means of hinges 15. These hinges are adjacent the hinges 14, and one strap of each hinge is attached to the door by means of the same rivets, screws or bolts that hold one strap of the hinge 15.

25 One strap of the hinge 15 has thereon a brace 30 element 16, which cooperates with a brace element 17 to prevent the bending of the door from the outside toward the inside of the building to which the door is attached. As shown in Figure 1, these brace elements are attached to the parts 35 3, 4 and 5, adjacent the line between the sections, so that when the door is closed and the sections are in alignment with each other, these braces abut and prevent the buckling of the door in a direction opposite to that in which the door bends 40 during the act of opening and closing. This brace 45 17 is attached to the door sections by means of the rivets or bolts which hold one strap of one of the hinges 6. These numerals 16 and 17 are used to designate brace elements used in connection with the hinges 15.

50 On the side of the pass door opposite the hinges 15 are braces 18 and 19 on sections 3 and 4, and braces 20 and 21 on the sections 4 and 5. These 55 braces serve the same purpose that braces 16

- and 17 do. By means of the hinges 6 and the braces 16, 17, 18, 19, 20 and 21 the door when in a vertical position is held substantially rigid. Any gust of air or any pressure on the outside 5 of the sectional door is overcome by means of these braces so that though there is provided in the sectional door this pass or wicket door the strength and rigidity of the sectional door are not materially affected thereby.
- 10 In order that the pass door may securely close the passageway through the sectional door there is provided, around the periphery of the door, in the wall thereof provided in the sectional door, a groove 22, into which a tongue 23 on the pass door fits. This construction is shown in Figure 8.
- 15 Each door section is composed of a plurality of panels. Section 1 has wooden panels 24. Sections 2 and 3 have glass panels 25, while sections 4 and 5 have wooden panels 26. These panels are shown in Figure 7 to be of three ply, giving greater strength and rigidity to the part of the door near the ground or bottom of the doorway. There is provided, in connection with the pass door, a lock 27, which engages a cooperating latch member 20 found in one section of the sectional door.
- 20 This sectional door is adapted to be used in connection with garages and other similar buildings. The operation and support of such a door are well known and form no part of the present invention. The present invention relates solely 25 to the formation of a pass door in connection with a sectional door of the overhead type, and means for strengthening the sectional door around the pass door so that the sectional door is not weakened by the formation therein of a pass door. It also pertains to the connection of parts of the 30 pass door so they will articulate with the sections of the main or overhead door.
- 35 I desire to comprehend within my invention such modifications as may be embraced within my claims and the scope of my invention.

Having thus fully described my invention, what I claim as new and desire to secure by Letters Patent is:

1. In combination, a hinge for hinging horizontally disposed sections and a hinge for hinging vertically disposed sections, and means attached to said respective hinges engaging one another to prevent inward movement of said sections under pressure on one side of the hinges. 5

2. In combination, a hinge for hinging horizontally disposed sections and a hinge for hinging vertically disposed sections, and means attached to said respective hinges engaging one another to prevent inward movement of said sections under pressure on one side of the hinges, 10 one of said hinges and said means being arranged on one side of the sections and the other of said hinges being arranged on the other side of the sections. 15

3. A new article of manufacture comprising a hinge formed of hinged plates, a hinge pin, a shoulder on one of said hinge plates, and an abutment plate having a corresponding shoulder engageable therewith. 20

4. A new article of manufacture comprising a hinge formed of hinged plates, a hinge pin, a shoulder on one of said hinge plates, an abutment plate having a corresponding shoulder engageable therewith, and a second hinge having hinge plates and a hinge pin arranged transversely of the first-mentioned hinge pin, said second hinge having one of its hinge plates connected to said abutment plate. 25

5. In combination, a transverse hinge on oppositely disposed vertical hinged door sections, 30 each section being attached to one part of said hinge, and an abutment plate on one of said sections engaging an abutment on a part of said hinge on the other section. 35

EDWARD HARRISON McCLOUD. 40
